UNITED STATES PATENT OFFICE.

RAYMOND E. J. DALEY, OF SCHENECTADY, NEW YORK, ASSIGNOR TO GENERAL ELECTRIC COMPANY, A CORPORATION OF NEW YORK.

SOUND-PRODUCING APPARATUS.

Application filed December 22, 1927. Serial No. 241,967.

My invention relates to apparatus for producing sound, and has for its principal object the provision of an improved apparatus and method of operation whereby electrical impulses 5 may be converted into sound or vice versa.

Various types of apparatus have been provided in the past for producing electrical impulses which are dependent either on sound or on the contour of a sound record or for producing sound which is dependent on such impulses. Many of these apparatus comprise an armature member which is mounted in a magnetic field, is mechanically 10 coupled to a vibratory member such as a stylus holder or a diaphragm, and is arranged to be moved in the magnetic field either in response to vibration of the magnetic flux or in response to vibration of the 15 diaphragm or stylus holder. In the operation of these apparatus, difficulty is frequently encountered due to the fact that the various parts of the apparatus tend to vibrate at their own free vibration periods 20 and distort the sound which it is desired to produce. In accordance with my invention, this difficulty is minimized by the provision of an improved mechanical coupling interposed between the armature and vibratory 25 member of the apparatus.

My invention will be better understood from the following description when considered in connection with the accompanying drawings and its scope will be pointed 30 out in the appended claims.

Referring to the drawings, Fig. 1 illustrates a sound producing apparatus or loud speaker wherein my invention has been embodied; and Fig. 2 illustrates a different 35 embodiment of my invention.

The improved apparatus comprises a conical diaphragm 1 which may be embossed or otherwise formed to give it the desired acoustical characteristic and is enclosed at 40 its back by a felt lined baffle 2 provided with felt covered openings 3. The conical diaphragm at its base is provided with a flange 4 which may be clamped between the edge of the baffle 2 and a member 5 by means 45 of screws 6, and at its apex is mechanically connected to an armature 7 through a mechanical coupling comprising driver rods 8 and 9 and a flexible member 10 which has 50 one of its ends interposed between the rods 8 and 9 and is fixed at its other end.

The armature 7 is supported between the pole pieces 11 and 12 of a permanent magnet or electromagnet 13 by means of a slotted resilient member 14 which is mounted on a support 15 attached to the pole piece 11 and 60 is arranged to have its tension adjusted by means of a cam 16 located at its upper end. The armature 7 is tapered at the end through which it is attached to the driver rod 9 and is slotted at its edges to receive 65 lugs on the inner periphery of the slotted member 14. One end of the resilient member 10 is attached to the pole piece 12. Adjustable resilient stops 19 and 20 are provided near the upper end of the armature 70 for the purpose of damping its movement. A coil 21 is mounted between the legs of the pole pieces 11 and 12.

With the exception of the mechanical coupling means interposed between the lower 75 end of the armature 7 and the apex of the conical diaphragm 1, this apparatus is claimed in a copending application of McKenzie Cottrell, Serial No. 239,775, filed Dec. 13, 1927.

As shown more clearly in Fig. 2, this coupling means comprises a hollow rigid tapered portion 16 connected between the rods 8 and 9 at its smaller end and connected through a resilient portion 17 at its larger 85 end to a supporting flange 18. It will be apparent that the resilient portion of the coupling means may be of tubular form, as illustrated by Fig. 2, or may be of any other suitable form, for example such as that 90 illustrated by Fig. 1.

The coupling means illustrated by both figures has the advantages that it has very little mechanical inertia, is very flexible in the desired direction of movement, is very 95 rigid in a direction transverse to the desired direction of movement, and renders possible any desired ratio between the motions of the armature and the diaphragm.

It has been found by extensive investigation that with the armature coupled to the diaphragm as described, the apparatus responds quite accurately to the electrical or mechanical impulses to which it is subjected and does not tend to produce objectionable 100 distortion of these impulses. It will of course be understood that when the apparatus is utilized as a loud speaker, or receiver, the coil 21 is subjected to current 105 which varies in accordance with the sound 110

to be produced and that, when the apparatus is used as a transmitter, the armature 7 is so moved as to produce in the coil 21 a flux change which produces electrical impulses dependent on the movement of the armature.

What I claim as new and desire to secure by Letters Patent of the United States is:

1. A sound producing apparatus comprising an armature, a vibratory member, and mechanical coupling means including a member provided with a hollow rigid portion connected between said armature and said vibratory member at one of its ends and resiliently supported at the other of its ends.
2. A sound producing apparatus comprising an armature, a vibratory member, and mechanical coupling means including a member provided with a tapered portion connected between said armature and said vibratory member at the smaller of its ends and resiliently supported at the larger of its ends.
3. A sound producing apparatus comprising an armature, a vibratory member, and mechanical coupling means including a

member provided with a hollow tapered portion connected between said armature and said vibratory member at the smaller of its ends and resiliently supported at the larger of its ends.

4. A sound producing apparatus comprising an armature, a vibratory member, and mechanical coupling means including a member provided with a tapered portion connected between said armature and said vibratory member at the smaller of its ends and supported at its larger end through a curved spring which is rigid in a plane transverse to the motion of said vibratory member.

5. A sound producing apparatus comprising an armature, a diaphragm, and mechanical coupling means including a member provided with a tapered portion connected between said armature and said diaphragm at the smaller of its ends and resiliently supported at the larger of its ends.

In witness whereof, I have hereunto set my hand this 20th day of December, 1927.

RAYMOND E. J. DALEY.
